United States Patent Office.

JOHN A. BASSETT, OF SALEM, MASSACHUSETTS.

Letters Patent No. 60,670, dated January 1, 1867.

IMPROVED CAPILLARY MATERIAL FOR FILLING GAS AND AIR CARBURETTORS.

The Schedule referred to in these Letters Patent and making part of the same.

TO ALL WHOM IT MAY CONCERN:

Be it known that I, JOHN A. BASSETT, of Salem, in the county of Essex, and State of Massachusetts, have invented a new and useful improvement in Absorbent and Capillary Material for Gas and Air Carburettors; and I do hereby declare that the following is a full, clear, and exact description of the same.

The object of this invention is to provide a cheap substitute for the more expensive capillary materials used as absorbents in gas and air carburettors, and to furnish a material which, from its great capillary power and extensive surface, will accomplish more perfectly the object in view.

It consists in the use of the fibres of wood prepared in the peculiar manner as herein presented. These fibres are torn from the wood by suitable machinery, so that the fibrous structure is preserved in the direction of the length of the grain, thus giving the fullest capillary power; and being finely divided, affords a great surface as a carburetting material and absorbent of the hydro-carbon liquid. I prefer to use it, when arranged in the carburetting apparatus, so that the fibres are placed perpendicularly and partially immersed in the hydro-carbon liquid; but it may be used in mass as it is sold and used as filling for mattresses, its commercial name being "excelsior."

Having thus described the nature of my invention, what I claim as new, and desire to secure by Letters Patent, is—

An absorbent and capillary material for gas and air carburettors, composed of the substance described, and prepared substantially in the manner set forth.

JOHN A. BASSETT.
